UNITED STATES PATENT OFFICE.

HENRY Z. YOUNG, OF SEVILLE, FLORIDA.

TILE-MACHINE.

SPECIFICATION forming part of Letters Patent No. 397,770, dated February 12, 1889.

Application filed July 26, 1888. Serial No. 281,113. (No model.)

To all whom it may concern:

Be it known that I, HENRY Z. YOUNG, of Seville, in the county of Volusia, and in the State of Florida, have invented certain new and useful Improvements in Tile-Machines; and I do hereby declare that the following is a full, clear, and exact description thereof.

My invention relates to tile-machines, and will be fully described hereinafter.

10 In the drawings, Figure 1 is a section of my improved tile-machine on line 1 1 of Fig. 2. Fig. 2 is a plan view. Fig. 3 is a vertical section on line 3 3, Fig. 2. Fig. 4 is a section on line 4 4, Fig. 1. Fig. 5 is a section on line 15 5 5, Fig. 2. Fig. 6 is a broken section on line 6 6, Fig. 5. Fig. 7 is a section on line 7 7, Fig. 2. Fig. 8 is a sectional view showing how the completed tiles are delivered; and Fig. 9 is a section on line 9 9, Fig. 8. Figs. 10 and 20 11 are details.

A A' are the pug-mills, which are provided with arms *a*, that serve, with arms *b* of shafts *B*, to mix the material as it passes down to the conveyers. The mill A is for the damp 25 core-sand, and A' is for the cement or clay of which the tiles are formed. Hollow conveyers *C* are located in the bottom of pug-mill A'. One end of each of these conveyers is provided with a pinion, *c*, and the two pinions are driven 30 from below by a larger pinion, *D*, on a shaft, *D'*, that has its bearings in uprights *D''*. In like manner mill A is provided with two conveyers, *E*, and these are driven by pinions *d*, which in turn are driven by a pinion, *D''*, 35 on shaft *D'*.

The conveyers *C* extend through the sides of the mill A' into barrels *F*, and the sand-conveyers *E* extend through the side of mill A into the conveyers *C*. The barrels *F* extend beneath the horizontal portion of a frame, *G*, and this frame is provided with dovetailed grooves in which blocks *e* slide, and to these blocks are hinged the arms *f* of a gate, *f'*, which, when down, closes the barrels *F*.

40 H are formers which are adapted to inclose the barrels while each two-pipe sections are being formed and to be gradually forced off of the barrels as the clay is packed in, and 45 these formers are connected by arms *h* with a turn-table, *I*, having grooves in which the

arms fit, and said arms are provided with hooked heads *i* for engagement with the spring-hooks *j*, that are carried by the turn-table. The arms are confined to the table by 55 keepers *j'*.

K is an arm that is hinged at one end to a bracket, *K'*, that is secured to the frame *G*, and near its hinged end this arm has a bearing for a pulley-shaft, *L*, which carries a friction-wheel, *M*, and two belt-pulleys, *M' M'*.

At its front end arm *K* is formed with branches *m m*, which branches are formed with arms *m' m'* and *m'' m''*. The arms *m'* form bearings for shafts *m³*, and between 65 these arms are the pulleys that drive these shafts. In like manner the arms *m''* form bearings for shafts *m⁴*. Those portions of the shafts *m³* and *m⁴* that project inside of the inner arms of the branches are squared to receive, respectively, convex reamers *N* and concave reamers *N'*, which are adapted to slide on their respective shafts under control of arms *O*, the ends of which loosely embrace their hubs. The arms *O* are connected by 70 toggle-links *O'* with a lever, *O''*, that is pivoted to a bracket, *O'''*, so that they can be advanced or withdrawn simultaneously by a single movement of the lever.

The pulleys that drive the shafts of the 75 reamers are connected with the pulleys *M' M'* by belts *M³*, and the friction-wheel *M* rests upon a horizontal friction-wheel, *M²*, the shaft *P* of which is stepped in a stand, *P'*, and carries a bevel-wheel, *P²*, on its upper end, that 80 engages with another bevel-wheel, *P³*, on a counter-shaft, *P⁴*. Just above its step shaft *P* carries two other friction-wheels, *p p*, which are far enough apart to receive between them a vertical friction-wheel, *p'*, the shaft *p²* of 85 which bears in a lever, *p''*, that is pivoted at one end to a stand, *Q*, and is supported at the other end by an arm, *Q'*, of stand *P'*, with springs *q* interposed between it and the arm above and below, as shown in Fig. 1. The end 90 of shaft *p²* opposite the wheel *p'* carries a cog-wheel, *p⁴*, for engagement with rack-teeth *p⁵* on a bar, *R*, which is slotted or looped at *R'* to receive the shaft *S* of the turn-table *I*, on which shaft it is supported and confined in 95 place by collars *s s*. The extreme forward end of the bar *R* is upturned and forked, as at *r*, 100

and this fork lies in the path of the down-turned end of an arm, T , of a pair of pushers, T' , which are carried by an arm, T^2 , that is hinged to a block, t , that slides in a dovetailed groove, t' , in the turn-table.

W is a lever that is pivoted at one end to pug-mill A', and from this lever is suspended a knife, W', and this lever is also connected by a wire or rope, W³, with a lever, W², that 10 operates a clutch, w, to throw pulley X in and out of gear, which pulley, through belt X' and pulley X², serves to drive the shaft D'.

The operation of my apparatus is as follows: As the material is packed in the barrels by the conveyers it forces the gate f' out, and the lower edge of the gate acting on lugs f^2 on the upper sides of bars h causes them to draw the barrels out to receive the pipe as it leaves the formers, and as the barrels 15 clear the formers the heads i engage with the catchers j . The attendant now drops the knife W' , and this throws pulley X out and stops the conveyers. The table is now revolved by hand until the barrels H are carried 20 between the reamers $N N'$, which ream the ends of the tiles, and then the table is further revolved a quarter-turn, and this brings the barrels H to the pushers T' , and also brings another pair of barrels in front of 25 the formers F . The gate f' and knife W' are then lifted and the barrels shoved over the formers and the gate again dropped. The lifting of the knife starts the conveyers and they begin to pack, and during the packing 30 an attendant lifts upon lever p^3 , and thus throws the friction-wheel p' up against wheel p , when the bar R will be driven forward to force out the pushers T' and cause them to drive the tiles from the barrels onto grooved 35 boards Y , that are placed upon cables Z to receive them. The attendant then pushes lever p^3 down and throws friction-wheel p' into contact with lower wheel, p , and the bar R is withdrawn, carrying the pushers T' back in 40 position for receiving another pair of barrels. Thus the tiles are formed, reamed, and expelled successively. 45

Having thus fully described my invention, what I claim as new, and desire to secure by Letters Patent, is—

1. In a tile-machine, the combination, with a pug-mill for the material of which the tiles are to be formed, of a hollow conveyer running through it, a conveyer for the core running through the first-named conveyer, a former inclosing the conveyers outside of the pug-mill, a barrel for receiving the tiles as they are formed, and a yielding gate for closing the formers during the formation of a tile, substantially as described. 55 60

2. The combination, with the conveyer and former, of the barrel, a revolving table, and an arm extending from the barrel to and upon the table, substantially as described.

3. The combination, with the former or 65
formers of a tile-machine, of a barrel or barrels,
a turn-table, an arm or arms connecting
the barrel or barrels with the turn-table, and
a reaming-frame and reamers adapted to re-
ceive the barrel or barrels while carried by 70
the table, and mechanism for driving the
reamers.

4. The combination, with the barrel or barrels, of the revolving table, a pusher or pushers carried thereby, a bar adapted to engage an arm of the pusher or pushers, and mechanism, substantially as described, for operating said bar to cause it to advance and withdraw the pusher or pushers at the proper times, substantially as described. 75
80

5. The combination, with the conveyers, formers, and barrels, of arms connecting the barrel with the table, and catches carried by the table and adapted to engage catch-heads on the arms, substantially as described. 85

6. The combination, with a pug-mill and conveyers, of a lever pivoted thereto, a knife carried by said lever, driving mechanism for the conveyers, and connections between said lever and driving mechanism, whereby when it is depressed it will throw said mechanism out of gear, substantially as described. 90

In testimony that I claim the foregoing I have hereunto set my hand, at Seville, in the county of Volusia and State of Florida, in the presence of two witnesses. 95
